LOUIS BERGER AND GEORGE A. HASSINGER, OF NEW ORLEANS, LOUISIANA.

NON-REFILLABLE BOTTLE.

1,136,762.

Specification of Letters Patent. Patented Apr. 20, 1915.

Application filed January 12, 1914. Serial No. 811,564.

To all whom it may concern:

Be it known that we, LOUIS BERGER and GEORGE A. HASSINGER, citizens of the United States, and residents of New Orleans, in the parish of Orleans and State of Louisiana, have invented a new and useful Improvement in Non-Refillable Bottles, of which the following is a specification.

This invention relates to non-refillable bottles, and one of the principal objects thereof is to provide a stopper which may be fitted into the neck of a bottle and which embodies means to permit permanent flow of the liquid from the bottle, but to prevent refilling of the same.

Another object of the invention is to provide means for preventing the retraction of the stopper from the bottle neck after the former has once been positioned therein.

20 A further object is to provide a device of the class described, which will be simple, durable, efficient in operation, and comparatively inexpensive to manufacture.

With these and other objects in view, which will become apparent as the description proceeds, the invention resides in the construction, combination and arrangement of parts hereinafter more fully described and claimed, and illustrated in the accompanying drawing in which like characters of reference indicate like parts throughout the several figures, of which,

Figure 1 represents a vertical, sectional view taken through the neck of a bottle, showing the device in position therein and showing the position of the parts when the bottle is in upright position, Fig. 2 represents a view similar to Fig. 1, showing the bottle as inverted, Fig. 3 represents a side 40 elevational view of the stopper, removed from the bottle, Fig. 4 represents a horizontal sectional view on the line 4—4 of Fig. 1, and, Fig. 5 represents a horizontal sectional view on the line 5—5 of Fig. 1.

45 Referring more particularly to the drawing, the numeral 5 represents the cylindrical neck of the bottle 6, and at 7 is shown a stopper which is cylindrical in shape, and which is positioned within the bottle neck, below the upper end thereof. The stopper is provided in its lower portion with a valve chamber 9, communicating at its upper end with the upper portion of the bottle neck through a restricted opening 10 formed by

an annular beading or flange 11 projecting 55 inwardly from walls of the stopper in spaced relation with the upper end thereof.

The valve chamber 9 is substantially funnel-shaped, being of a greater diameter at its upper than at its lower end, and has seated 60 therein a substantially egg-shaped valve 12, adapted, when the bottle is in upright position as shown in Fig. 1, to drop into the lower end of chamber 9 to close the same and to prevent filling of the bottle, as will 65 be readily understood. The upper or larger end of the valve is provided with a plurality of spaced radially extending, substantially triangularly shaped lugs 8 whose upper edges fall in a common place at right angles 70 to the longitudinal axis of the valve, and whose purpose is to prevent seating of the larger end of the valve in the opening 10 when the bottle is entirely inverted, so that the liquid contained in the bottle may pass 75 around the valve through the opening.

Positioned above the restricted opening 10 is a substantially frusto-conical disk 13 of a diameter less than the diameter of the upper end of the stopper, but slightly 80 greater than the diameter of the restricted opening, and connected by means of spaced arms 14 with the walls of the stopper, so that the contents of the bottle, when the same is inverted, may flow around the disk 85 13, between arms 14. The disk is adapted to co-act with the flange or beading 11, to prevent the insertion of a wire or other instrument for opening of the valve 12 or for holding the same in open position when the 90 bottle is returned to an upright from an inverted position, and the flange 11 also acts as a stop to limit the outward movement of valve 12 from its seated position. Near the lower end of the stopper, the same is provided with an annular groove 15, on its outer surface, which co-acts with a reduced lower end portion 16 of the stopper for forming an annular flange or collar 17, occurring between the reduced portion and 100 groove 15, and a plurality of springs 18 are secured in spaced relation in any desired manner at their lower ends to collar 17, and at their upper ends are bent outwardly, then inwardly so that they may be housed within the groove 15, when forced toward the stopper incident to the insertion of the latter within the bottle neck, the normal tendency 105

of the springs, however, acting to project the upper ends thereof outwardly from the groove.

The springs are adapted to engage an annular shoulder 19, formed in the bottle neck 5, by means of an outwardly enlarged annular portion 6^a of the bottle neck, to prevent retraction of the stopper, once the same has been positioned in the bottle neck, said annular enlarged portion at its lower end as at 20 where it joins the lower portion 21 of the bottle neck, being of a diameter somewhat less than the diameter of the upper portion of the bottle neck, so that the reduced portion 16 of the stopper snugly fits in the lower portion of the neck, and when the stopper is in position the flange or collar 17 overhangs the portion 20 and is adapted to rest against a compression ring 22, seated thereon, so that there will be no rattling or movement of the stopper after the same has been put in place, as will be readily understood.

In order to readily position the valve 12 within the valve chamber 9, a portion of the lower end of the stopper has been made of a separate semi-tubular piece A, which forms substantially one-half of the wall of the valve chamber and which extends from just below flange 11 to the bottom end of the stopper, and which is held in place by the action of the spring 18, carried by that section and by the fact that it is embraced by the walls of the upper and lower portions of the bottle neck, as will be readily understood, it being obvious that the valve 12 is positioned in the valve chamber, and the sections A fitted into place before the stopper is placed in position within the neck of the bottle. It will be understood that the bottle is first filled, and the stopper then inserted into the neck of the bottle, and subsequently a cork B placed within the bottle neck above the stopper, the frusto-conical disk 13 acting as a limit to the inward movement of the cork.

When the contents of the bottle are to be removed, the cork should be taken out and the bottle partially inverted, so that the valve 12 will drop from its seated position into the enlarged upper end of the valve chamber 9, resting on the lowermost surface of the chamber when the bottle is in the position shown in Fig. 2, the movement of the

valve 12 being limited by the flange 11 against which it rests, allowing the contents of the bottle to pass through chamber 9, around the valve 12, through the restricted opening 10 and out around the disk 13, through the upper end of the bottle neck. The bottle may be entirely inverted in pouring its contents, or it may be partially inverted, as shown, however in either case the lugs 8 will prevent choking of the passage 10 by the valve. After the stopper has once been positioned in the neck of the bottle it will be impossible to remove the stopper without breaking the neck, since the springs 18 cannot be retracted from their engagement with shoulder 19, and since the stopper may not be forced into the body of the bottle for the reason that the inward movement of the stopper is limited by the flange 17.

Although we have described the preferred embodiment of our invention, we may desire to make such changes in the construction, combination and arrangement of parts as do not depart from the spirit of the invention and the scope of the appended claim.

We claim:

The combination with a bottle having a neck, of a stopper adapted to fit into said bottle neck, means to prevent retraction of said stopper from said neck, said stopper having a substantially funnel-shaped chamber communicating with the interior of the bottle, said chamber communicating by a restricted opening having convex walls with the upper end of the bottle neck, a substantially egg-shaped valve adapted to seat in the smaller end of the chamber when the bottle is in upright position, and adapted to unseat when the bottle is inverted, a frusto-conical disk positioned adjacent the restricted opening and being of a diameter greater than the diameter of the opening, arms connecting said disk with the walls of the stopper, and a plurality of triangularly shaped radially disposed lugs on the larger end of the valve to prevent seating of the valve in the restricted opening.

LOUIS BERGER.

GEORGE A. HASSINGER.
